UNITED STATES PATENT OFFICE.

ADÈLE AMÉLIE LONGUEMARE, OF PARIS, FRANCE.

CUSHIONING DEVICE FOR AUTOMATIC DILUTION-VALVES IN CARBURETERS.

No. 878,077.

Specification of Letters Patent.

Patented Feb. 4, 1908.

Application filed January 16, 1907. Serial No. 352,359.

To all whom it may concern:

Be it known that I, ADÈLE AMÉLIE LONGUEMARE, (née LECHEZNE,) a citizeness of the French Republic, and residing at Paris, in France, have invented a certain new and useful Cushioning Device for Automatic Dilution-Valves in Carbureters, of which the following is a specification.

This invention relates to a pneumatic cushioning device, applicable generally to any movable part capable of being violently moved under the action of a variation of pressure, this device being more particularly designed for use for the automatic regulation of the admission of supplementary air in the explosion engines.

In the accompanying drawing, given merely by way of example, Figure 1 is a vertical section through the carbureter of an explosion engine, provided with a cushioning device according to the present invention. Fig. 2 is a plan of the essential member constituting this invention. Fig. 3 is a partial elevation of the bottom air-inlet nozzle. Fig. 4 is a modified construction.

In principle, this pneumatic cushioning device consists of a hollow piston of constant capacity, provided at both its faces with holes of adjustable area, the said piston moving, under the action of a pressure applied externally to its rod, in a closed cylinder, also of constant capacity, so as to make the air forced above or below the said piston, to pass into chambers of variable volume.

In the construction shown in Figs. 1 to 3, of such a device applied, by way of example, to the automatic regulation of the admission of additional air to an explosion engine, the hollow piston *a* is arranged in a completely closed cylindrical body *b* to the interior of which access can be gained by means of an air-tight cap *c*. This hollow piston *a* is provided on its two faces with a certain number of holes *d* and *e*. The holes *d* of the upper face can be partly, or entirely, closed by a movable disk *k* held at its center against the said face by means of a nut which is screwed to the end of a central rod *f* passing through the bottom cover of the cylindrical body *b*.

The said rod *f* is connected to a cylindrical sleeve or flanged disk *g* sliding with a slight amount of friction in another cylindrical body *h* arranged in line with the piston *a* and open at the bottom. The sleeve *g* is provided with a cover preventing any air from getting in through the open base of the cyl-

inder *h*, and its cylindrical wall or flange is provided with openings *i* which coöperate with windows *j* made in the wall of the said cylinder *h*.

The openings *i* and *j* are arranged so that they coincide when fully open, that is to say when the hollow piston *a* is at the top of its upstroke.

It is these openings *i* and *j* which in the application illustrated, afford passage to the additional air intended to insure automatic working of the cushioning device.

A projection *l* secured to the sleeve *g*, slides in a longitudinal groove *o* of the cylindrical body *h*. This projection insures vertical guiding of the whole mechanism constituted by the hollow piston *a*, the rod *f* and the sleeve-valve *g*.

Through the chamber of the cylindrical body *h* passes horizontally a perforated pipe *p* of which one of the ends is fitted into a branch *m* through which arrives the explosive mixture coming from the carbureter, the other end of the said pipe *p* opening into the branch *n* for the inlet of the said mixture to the engine.

The working is as follows:—When the engine is working at high speed a strong depression is produced in the branch *n*, and consequently in the chamber of the cylinder *h*, the said depression acting strongly on the sleeve valve *g* which is caused to rise and increase the section of the inlet passages *i* and *j* available for the admission of the additional air.

The jerky movements, generally produced in automatic valves or other devices regulating the admission of additional air, are avoided by this new device, owing to the cushioning action of the air, which cannot pass through the hollow piston *a* except with a speed depending on the section of the passage left by the holes *d* and *e*, the invariable capacity of the hollow piston *a* serving as moderator to the movements of the said piston during the circulation of air from one of the chambers of the cylinder *b* into the other chamber.

The cross-sectional area of the holes *d* and *e* is regulated once for all in accordance with the power of the engine to which the device is applied.

When depression varies in the cylindrical body *h*, either owing to a change of speed of the engine, or to the butterfly valve *r* being operated so as to throttle or increase the ad-

mission of the mixture to the engine, it follows that the travel of the sleeve-valve *g* is varied to a corresponding extent, and the hollow piston *a* is moved with variable energy, in such manner that the jerky movements which might take place owing to variable depressions, are compensated by the cushioning action caused by the circulation of air through the chamber of the hollow piston *a*.

10 The holes *t* made in the cylinder *h* and uncovered when the engine is working at a small speed, serve to avoid condensation of the petrol owing to the small draft of air produced.

15 In the construction shown in Fig. 4, the rod *f* is done away with and the hollow piston *a* is connected direct to the sleeve *g*. In this case, the movable disk *k* serving to regulate

20 the passage of air through the holes *d* is mounted on a small spindle preferably provided with a milled head *q* or with a screw. The regulation of the said holes *d* is effected by hand as before, after having unscrewed 25 the air-tight cap *c*.

When applied to an explosion engine, a cushioning device according to the present invention enables homogeneity of the mixture to be assured by the suppression of the shocks 30 in the movements of the additional air inlet valve whatever be the speed of the engine.

What I claim as my invention and desire to secure by Letters Patent is—

1. In a device of the character described 35 the combination with a member movable by variations of pressure, of a closed cylinder, a hollow piston in said cylinder and provided in each face with a plurality of holes, and an operative connection between said piston and 40 said member.

2. In a device of the character described the combination with a member movable by variations of pressure, of a closed cylinder, a hollow piston in said cylinder and provided 45 in each face with a plurality of holes, adjustable means to vary the total area of said holes and an operative connection between said piston and said member.

3. In a device of the character described 50 the combination with a member movable by variations of pressure, of a closed cylinder, a hollow piston in said cylinder and provided in each face with a plurality of holes, adjustable means to close one of said holes and an

operative connection between said piston 55 and said member.

4. In a device of the character described the combination with a member movable by variations of pressure, of a closed cylinder, a hollow piston in said cylinder and provided 60 in each face with a plurality of holes, adjustable means to close any desired number of said holes and an operative connection between said piston and said member.

5. In a device of the character described 65 the combination with a member movable by variations of pressure, of a closed cylinder, a hollow piston in said cylinder and provided in each face with a plurality of holes, a disk of smaller diameter than said piston applied 70 to one face thereof for the purpose described, and an operative connection between said piston and said member.

6. The combination of a closed cylinder, a hollow piston therein provided in each face 75 with a plurality of holes, a cylindrical body in line with said cylinder and provided in its wall with holes, a flanged disk movable lengthwise but not rotatable, in said cylindrical body the flange of said disk being 80 provided with holes and the holes in the cylindrical body being so arranged as to correspond with the flange holes at one position of the flange relatively to the said body, and a piston rod connecting said piston and 85 flanged disk.

7. In a device of the character described the combination of a closed cylinder, a hollow piston therein provided in each face with 90 a plurality of holes, adjustable means to vary the total area of said holes, a cylindrical body in line with said cylinder and provided in its wall with holes, a flanged disk movable lengthwise but not rotatable in said cylindrical body, the flange of said disk being 95 provided with holes, the holes in the cylindrical body being so arranged as to correspond with the flange holes at one position of the flange relatively to the said body, and a piston rod connecting said piston and flanged disk. 100

In testimony whereof I have signed my name to this specification in the presence of two subscribing witnesses.

ADÈLE AMÉLIE LONGUEMARE.
